CLAIM

The ornamental design for a syringe, as shown and described.

DESCRIPTION

FIG. 1 is a front perspective view of a syringe, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a cross-sectional view thereof taken along line 8-8 of FIG. 2;

FIG. 9 is another view of FIG. 8 showing a transparent cylindrical portion by dark highlight;

FIG. 10 is a cross-sectional view thereof taken along line 10-10 of FIG. 2;

FIG. 11 is a cross-sectional view thereof taken along line 11-11 of FIG. 2;

FIG. 12 is a cross-sectional view thereof taken along line 12-12 of FIG. 2; and,

FIG. 13 is a transparent front perspective view thereof showing a transparent cylindrical portion by dark highlight.
